[57] CLAIM

The ornamental design for a sidewall for a bottle, as shown and described.

DESCRIPTION

FIG. 1 is a top front perspective view of a sidewall for a bottle showing my new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof; and,

FIG. 7 is a bottom plan view thereof.

The broken lines showing the bottle neck and base are for illustrative purposes only and do not form part of the claimed design.
